(57) **CLAIM**

The ornamental design for modular tank, as shown and described.

DESCRIPTION

FIG. 1 is a perspective view of a modular tank showing my new design;

FIG. 2 is a top plan view of the modular tank of FIG. 1;

FIG. 3 is a front elevational view of the modular tank of FIG. 1, a rear elevational view being equivalent;

FIG. 4 is a bottom plan view of the modular tank of FIG. 1; and,

FIG. 5 is a left side elevational view of the modular tank of FIG. 1, a right side elevational view being equivalent.

The broken line showing of the environment is for illustrative purposes only and forms no part of the claimed design.
